FLUID IMPACT PULVERIZER

William A. Thomas, Pittsburgh, Pa., assignor to
 Blaw-Knox Company, Pittsburgh, Pa., a corpora-
 tion of New Jersey

Application December 29, 1945, Serial No. 637,820

6 Claims. (Cl. 241—39)

1

This invention relates to apparatus for pulverizing solids by impact of particles with each other while traveling at high speed, and to means for separating and removing the particles which have been reduced to the desired fineness, and returning the oversize particles for further grinding.

Impact grinders or pulverizers utilizing a gas under pressure as a motive fluid have been known heretofore but have been subject to certain limitations. It is the object of my invention to provide improved impact pulverizing apparatus of simple construction, capable of effecting the desired pulverization with a minimum consumption of steam and other desirable operating characteristics such as preliminary removal of dust or fines from the material to be pulverized, uniformity in the fineness of the product at various rates of feed, and the ability to grind material having a considerable moisture content, as readily as relatively dry material.

In a preferred embodiment, the invention comprises a closed vessel, conveniently a cylindrical tank, with its axis vertical, a pair of opposed gas-jet injectors in the lower portion thereof and a feeder thereabove for delivering solid material to be reduced in the form of coarse particles or small lumps for pulverization by impact. Above the feeding means I provide a classifier chamber having a circumferential inlet opening. Guide vanes spaced around the opening impart a tangential velocity component to the entering gas stream entraining solid particles of various sizes. An outlet pipe extending centrally into the classifier permits the escape of particles which have been reduced sufficiently in size to float in the outflowing gas. The lower portion of the classifier is in the form of a hopper for collecting oversize particles and returning them to the entering stream of solid material. An important feature of the invention is the provision of a positive downward force on the oversize particles which tends to insure effective separation therefrom from the finer floating particles.

Further details, novel features and advantages of the invention will be explained during the following complete description which refers to the accompanying drawings illustrating a preferred embodiment of the invention and a typical system in which it is adapted to serve, viz., apparatus for supplying pulverized coal to a furnace for combustion.

In the drawings:

Figure 1 is a diagrammatic elevation with a portion in section showing a complete system for

2

supplying pulverized coal for combustion, including my invention;

Figure 2 is an elevation partly broken away showing the pulverizer of my invention with a portion in central vertical section;

Figure 3 is a vertical section taken along the plane of line III—III of Figure 2;

Figure 4 is a horizontal section taken along the plane of line IV—IV of Figure 3;

10 Figure 5 is a portion of Figure 3 to enlarged scale; and

Figure 6 is a partial horizontal section taken along the plane of line VI—VI of Figure 5.

Referring in detail to the drawings, the invention is particularly useful in the pulverization of coal for combustion, although it is by no means limited to this specific application. It will be described in detail, however, with reference to such application. As shown in Figure 1, the pulverizer indicated generally at 10 is adapted to

15 receive coal from a storage hopper 11 by means of a screw conveyor 12 which discharges into the inlet of a feeding mechanism 13. The feeding mechanism is preferably of the injector type disclosed in detail and claimed in my copending application, Serial No. 637,819, filed December 29, 1945, Patent No. 2,420,388 for Apparatus for Feeding Granular Material into a Fluid Stream. Pulverized coal produced by my invention flows

20 through a delivery pipe 14 to a separator 15 of known construction effective to separate most of the coal from the motive fluid, usually superheated steam. The coal falls into a burner 16 which is supplied with air for combustion by a blower 17 through a pipe 18. The fuel and air are fired into a furnace or other combustion space 19. Steam discharged by the separator 15 flows through a pipe 20 with only a small portion of the coal into the combustion space 19.

Referring now more particularly to Figures 2 through 6 for a detailed description of the pulverizer 10, it will be seen that it comprises a cylindrical tank having a side wall 21, a bottom 22 and a top or cover 23. A pair of opposed injectors 24 are disposed in the tank at a level somewhat above the bottom 22. Each injector comprises a nozzle 25 connected to a suitable source of motive fluid, such as superheated steam, and

25 a throat 26. The nozzle is mounted radially on the side wall of the tank while the throat is carried by a strut 27 extending upwardly from the bottom 22. As shown, the two injectors are axially aligned and spaced slightly apart. As a result, they are adapted to discharge jets of steam

and solid particles entrained therewith into direct or head-on collision.

The feeding means 13, as previously stated, is of the injector type and includes a Venturi throat 28 and a nozzle 29 connected to a suitable source of gas under pressure such as superheated steam. In accordance with well-known principles, the injector serves to discharge into the interior of the pulverizer 10 a jet of steam entraining solid particles drawn in through the inlet indicated at 30 in Figure 1. In the particular example being described, the solid material is coal which has been initially reduced to particles of approximately $\frac{1}{2}$ " in diameter. The feeding means 13 has an outlet or mouth 31. Coal discharged therefrom strikes a concave deflector plate 32 mounted on the sidewall 21 of the tank. On striking the deflector the coal particles rebound and fall downwardly with some fragmentation and the resulting particles are, after a certain amount of eddying and helter-skelter circulation, entrained by the steam jets delivered to the injectors 24 by the nozzles 25. As shown in the drawings, the axis of the feeding mechanism 13 lies in a vertical plane normal to the vertical plane through the axes of the injectors 24. The injectors, as already stated, discharge jets of steam and particles into direct collision whereupon further fragmentation of the particles occurs.

Any dust or similar fine particles accompanying the coal delivered into the pulverizer by the feeding means 13 are floated upwardly by the general movement of the steam within the pulverizer in that direction. Such material needs no further grinding and, because of its fineness, floats readily upward and is thus effectively separated from the larger particles which are drawn into the injectors as just explained. Additional fine particles produced by the collision of coarser particles in the space between the discharge ends of the injectors 24 also float upwardly in the ascending mass of steam. Coarser particles may accumulate on the bottom of the pulverizer but are agitated by the jets from injector 28, 29 and eventually are again drawn into the steam jets of the injectors 24 and subjected to further impact. Thus all the material delivered to the pulverizer is progressively reduced to a fineness such that it can escape by flotation in the upwardly moving steam.

A classifier 33 in the upper portion of the tank comprises a cylindrical chamber open at the top. The chamber is supported from the cover 23 on hangers 34 so that the upper edge of the chamber is spaced a substantial distance below the top of the tank, leaving a circumferential opening or inlet for steam and floating particles of coal or other solids. An outlet 35 extends centrally through the top 23 and downwardly into the chamber 33 terminating at a level below the upper edge thereof. This outlet is connected to delivery pipe 14. Vertically disposed guide vanes 36 are hinged at their outer edges in a ring 37 secured to the top of the chamber 33 and a plate 38 secured to the cover 23. A ring 39 having radial slots 40 rests on the upper edges of the vanes 36. The vanes have projections 41 extending upwardly from their inner edges into the slots 40. Thus by slight angular movement of the ring 39, the angular position of all the vanes may be simultaneously adjusted. To permit such adjustment, an actuating shaft 42 having a handle 43 is secured to

one of the vanes and extends upwardly through the cover 23.

The vanes 36 are adjusted to impart a tangential velocity component to the steam and coal particles flowing upwardly through the space between the chamber 33 and the tank wall 21 and inwardly into the former. This creates a vortex in the chamber from the center of which steam and fine particles floating therein ascend through the outlet 35 and flow through the pipe 14 to the separator 15. Coarser particles which arrive in the chamber 33 are thrown outwardly by centrifugal force and thus removed from the steam ascending into the outlet 35. These coarser particles travel around inside the chamber 33 and fall gradually into a hopper 44 therebelow. The lower end of the hopper is connected to a branch opening 45 in the outlet 31 of the feeding mechanism and thus returns the coarser particles to the entering stream of solid for further grinding by repeated impact as previously described. The jet of steam and solid material delivered by the feeding means 13 creates a positive down draft through the chamber 33 and hopper 44 and thus prevents any tendency of the rising steam to pass through the classifier in the reverse direction.

It will be apparent from the foregoing that the invention provides a pulverizer having numerous advantages over similar devices known heretofore. The apparatus is simple and compact and requires no particular attention during operation. The continuous circulation of solid material repeatedly through the opposed injectors causes it to be progressively reduced in size until it is fine enough to float in the outgoing steam. The separation of the fine particles takes place in two stages, the first occurring as the material is initially fed into the tank. Any fines accumulated with the larger particles are immediately floated upwardly along with those resulting from repeated impacts of previously fed particles. This preliminary dedusting of the entering material increases the total output since it removes from the zone of active pulverizing that portion of the entering material which is already fine enough to require no further grinding. The second stage of separation, of course, takes place in the classifier chamber 33, the finer particles ascending from the center of the vortex with the outgoing steam and the larger particles being thrown against the wall of chamber 33 and drawn downwardly into the hopper 44 and thence to the entering stream of fresh material.

The invention has the further advantage that the operating rate may be varied without materially affecting the fineness of the product. The volume of material ground may be varied by changing the rate of feed and without altering the amount of steam. The steam consumption per pound of solid ground is such that the operating cost is not excessive. The apparatus is capable of grinding fuel with as much as 10% moisture. This was impossible with previous devices and it was necessary for users thereof to burn coal having a very low moisture content, despite a price differential in favor of the fuel having more moisture.

The fineness of the product ascending through the outlet may be controlled by varying the angle of the classifier vanes. The greater the tangential velocity of the entering steam and entrained solid particles, the smaller the particles which are thrown to the outskirts of the central vortex in the chamber and the finer, therefore,

are the particles which actually escape. The apparatus exhibits a satisfactorily low rate of wear despite the abrasive quality of the material being pulverized.

Operation of the apparatus results in the building up of only a small accumulation of partly ground material in the bottom of the tank and this is promptly disposed of when the input of solid material is discontinued. The amount of this accumulation, furthermore, does not build up as the rate of operation is increased.

It will be understood that changes in the construction illustrated and described may be made within the scope of my invention. Instead of relying on the jet of incoming material to produce a positive down draft through the classifier hopper, a separate steam jet injector may be employed. On the other hand, the hopper may be constructed to deliver adjacent the inlets of the injectors 24. As a further alternative provision a helical flight or vane may be mounted in the hopper of the classifier. Other modifications may also be made such as utilizing the reduction in pressure at the inlets of the injectors 24 to draw in fresh material, instead of providing the separate feeding means shown at 13. The internal shape of the throats 26 of the injectors may be varied but that illustrated has proved to be highly effective.

It will be understood that the aforementioned modifications as well as other changes in the details of construction are contemplated within the scope of the following claims.

I claim:

1. In an impact pulverizer for solid particles, in combination, a closed chamber, a pair of horizontally extending injectors having open-ended throats with both of their ends opening directly in said chamber, nozzle means for injecting a gaseous fluid under pressure through said injectors, said pair of injectors being coaxial and in opposed relation to one another across an unobstructed impact zone to force said particles to collide, means for withdrawing gaseous fluid and finer particles from said chamber at a vertically spaced zone above the injectors, means for injecting a stream of solids and gas directly into said chamber between said withdrawal means and said injectors, said injection being directed at a downward angle to a horizontal plane through the axes of said injectors and sufficiently near the plane of the injectors to assist in maintaining a circulation of the solids in said chamber.

2. In an impact pulverizer for solid particles, in combination, a closed chamber, a pair of horizontally extending injectors having open-ended throats with both of their ends opening directly in said chamber, nozzle means for injecting a gaseous fluid under pressure through said injectors, said pair of injectors being coaxial and in opposed relation to one another across an unobstructed impact zone to force said particles to collide, means for withdrawing gaseous fluid and finer particles from said chamber at a vertically spaced zone above the injectors, means for injecting a stream of solids and gas directly into said chamber between said withdrawal means and said injectors, said injection being directed at a downward angle to a horizontal plane through the axes of said injectors and sufficiently near the plane of the injectors to assist in maintaining a circulation of the solids in said chamber, the interception of said angle with said plane being outside said impact zone.

3. In an impact pulverizer for solid particles, in combination, a closed chamber, a pair of horizontally extending injectors having open-ended throats with both of their ends opening directly in said chamber, nozzle means for injecting a gaseous fluid under pressure through said injectors, said pair of injectors being coaxial and in opposed relation to one another across an unobstructed impact zone to force said particles to collide, a classifier vessel mounted in said chamber generally above said injectors, means for withdrawing gaseous fluid and finer particles from said chamber through said classifier vessel, said classifier vessel having a lower portion forming a hopper having a discharge opening emptying into said chamber to return the coarser portions of said finer particles to said injectors, and means for injecting a stream of solids and gas directly into said chamber between said classifier vessel and said injectors, said injection being directed at a downward angle to a horizontal plane through the axes of said injectors and sufficiently near the plane of the injectors to assist in maintaining a circulation of the solids in said chamber.
4. In an impact pulverizer for solid particles, in combination, a closed chamber, a pair of horizontally extending injectors having open-ended throats with both of their ends opening directly in said chamber, nozzle means for injecting a gaseous fluid under pressure through said injectors, said pair of injectors being coaxial and in opposed relation to one another across an unobstructed impact zone to force said particles to collide, a classifier vessel mounted in said chamber generally above said injectors, means for withdrawing gaseous fluid and finer particles from said chamber through said classifier vessel, said classifier vessel having a lower portion forming a hopper having a discharge opening emptying into said chamber to return the coarser portions of said finer particles to said injectors, and means for injecting a stream of solids and gas directly into said chamber between said classifier vessel and said injectors, said injection being directed at a downward angle to a horizontal plane through the axes of said injectors and sufficiently near the plane of the injectors to assist in maintaining a circulation of the solids in said chamber, said hopper being connected to said last-mentioned means to assist in the return of said coarser portions to said injectors.
5. In an impact pulverizer for solid particles, in combination, a closed chamber, a pair of horizontally extending injectors having open-ended throats with both of their ends opening directly in said chamber, nozzle means for injecting a gaseous fluid under pressure through said injectors, said pair of injectors being coaxial and in opposed relation to one another across an unobstructed impact zone to force said particles to collide, means for withdrawing gaseous fluid and finer particles from said chamber at a vertically spaced zone above the injectors, an injector-type feeding means having its outlet mouth discharging directly into said chamber immediately adjacent said impact zone between said withdrawal means and said injectors to assist in maintaining a circulation of the solids in said chamber, said feeding means being directed at a downward angle to a horizontal plane through the axes of said injectors, the axis of said feeding means lying in a vertical plane normal to the plane through the axes of said injectors and substantially eccentric relative thereto.
6. In an impact pulverizer for solid particles,

in combination, a closed chamber, a pair of horizontally extending injectors having open-ended throats with both of their ends opening directly in said chamber, nozzle means for injecting a gaseous fluid under pressure through said injectors, said pair of injectors being coaxial and in opposed relation to one another across an unobstructed impact zone to force said particles to collide, a classifier vessel mounted in said chamber generally above said injectors, means for withdrawing gaseous fluid and finer particles from said chamber through said classifier vessel, said classifier vessel having a lower portion forming a hopper having a discharge opening emptying into said chamber to return the coarser portions of said finer particles to said injectors, means for feeding gas and fresh particles to said chamber between said classifier vessel and said injectors, said means being directed at a downward angle to a horizontal plane through the axes of said injectors and sufficiently near the plane of the injectors to assist in maintaining a circulation of the solids in said chamber, and gas feeding means to assist in the return of said coarser portions to said injectors and prevent any reversal in the direction of flow in the lower portion of said classifier vessel.
